MUZZLE ATTACHMENT FOR GUNS

Samuel G. Green, Gray, Ga.

Application October 29, 1936, Serial No. 108,222

1 Claim. (Cl. 89—14)

(Granted under the act of March 3, 1883, as
amended April 30, 1923; 370 O. G. 757)

The invention described herein may be manufactured and used by or for the Government for governmental purposes, without the payment to me of any royalty thereon.

This invention relates to a muzzle attachment 5 for guns and more particularly it has reference to that class of attachments serving to check recoil, silence the report, eliminate smoke and conceal flash.

The purpose of the invention is to provide an 10 efficient inexpensive attachment which may be readily disassembled for cleaning and replacement and which will be heated uniformly throughout its length to establish a condition of 15 operation that is especially favorable for prolonged firing.

To these and other ends the invention consists in the construction, arrangement and combination of elements described hereinafter and pointed out in the claim forming a part of this 20 specification.

A practical embodiment of the invention is illustrated in the accompanying drawing, wherein:

Fig. 1 is a longitudinal sectional view of the 25 improved muzzle attachment applied to the jacket of a gun.

Fig. 2 is a view in side elevation of the inner tube.

Fig. 3 is a sectional view on the line 3—3 of 30 Fig. 1.

Fig. 4 is a longitudinal sectional view showing the attachment applied to a gun barrel.

Referring to the drawing by characters of reference there is shown the front portion of a machine gun comprising a reciprocable gun barrel 35 5 whose muzzle is mounted in a bearing 6 threadedly attached to the front plate 7 of a water jacket 8.

The bearing 6 projects from the jacket and 40 threadedly carries a large cylindrical block 9 which is assembled onto the bearing before the bearing is inserted in the front plate of the jacket. The block is locked in place on the bearing by a set screw 10 which is threaded in the front face of the block and selectively engages in one of a number of semi-circular recesses 11 formed marginally in a flange 12 on the front end of the bearing. The block serves as a radiator and the muzzle of the gun barrel and it has a reduced 45 threaded outer end 13 for carrying the muzzle attachment.

The attachment is conveniently formed of two 50 parts comprising a perforated inner tube 14 and an imperforate outer tube 15. The inner tube

has a thickened base 16 whereby it is threadedly mounted on the end 13 of the block and whereby it threadedly receives the outer tube and holds it spaced from the inner tube to provide an annular expansion chamber 17 open at its front end.

The inner tube is adapted to provide a cylindrical expansion chamber 18 in its rear portion and a forwardly constricted recompression chamber 19 in its front portion which terminates in a cylindrical outlet 20. The rear chamber 18 is 10 of short length and has a large diameter which is in excess of its length and which has a relation to the bore of the gun barrel of about four to one. The front chamber is approximately twice the length of the rear chamber and the outer wall 15 21 of the front chamber is tapered to provide a large outlet 22 for the annular chamber 17.

The inner tube is provided with a plurality of 20 rows of apertures 23 progressively decreasing in size from rear to front. When a projectile is fired from the gun barrel the gases from the propellant powder charge and the unconsumed particles of the charge issue from the muzzle and enter the expansion chamber 18. At this point the gases rapidly expand and a portion thereof 25 discharges at relatively low velocity through the larger apertures 23. The remainder of the gases and the unconsumed particles of powder continue forward into the recompression chamber 19 and are discharged at high velocity through the smaller apertures 23 and into the annular chamber 17. 30 This laterally directed portion of the gases moves into the gas stream that entered the chamber 17 through the larger apertures and since expansion in the chamber 17 is more or less unrestricted, the intermingling gases set up a condition of eddies and cross currents that tends to extinguish or suppress flame propagation. The gases issuing from the expansion chamber prevent back pressure and the lateral diversion of the gases from the recompression chamber prevents accumulation 35 and ignition in front of the outlet 20. This arrangement is especially favorable for prolonged firing as the attachment is uniformly heated throughout its length to a desired temperature 40 of 900 to 950 degrees.

In Fig. 4 the inner tube 24 and outer tube 25 are threadedly connected to an adapter 26 which in turn is threadedly connected to a gun barrel 27. The adapter is formed to provide an expansion chamber 28 flaring from a point directly in front of the barrel and merging with the cylindrical expansion chamber 23. The arrangement and structure of the inner and outer tubes is similar to that of Fig. 1.

I claim;

In combination, a gun barrel, an attachment at the muzzle of the barrel comprising an imperforate outer tube, an inner tube connected at its rear end to the outer tube and spaced therefrom to provide an annular expansion chamber, said inner tube having at its rear a short expansion

chamber of a diameter approximately four times the caliber of the gun barrel and having at its front a tapered recompression chamber approximately twice the length of the rear expansion chamber, and said inner tube having a plurality of apertures decreasing in size from rear to front.

SAMUEL G. GREEN.
